UNITED STATES PATENT OFFICE.

MAURICE F. HEALY, OF WATERTOWN, MASSACHUSETTS.

WEIGHT HOISTING AND RELEASING MECHANISM.

1,320,688.

Specification of Letters Patent.

Patented Nov. 4, 1919.

Application filed July 21, 1919. Serial No. 312,442.

(FILED UNDER THE ACT OF MARCH 3, 1883, 22 STAT. L., 625.)

To all whom it may concern:

Be it known that I, MAURICE F. HEALY, a citizen of the United States, and a resident of Watertown, in the county of Middlesex and State of Massachusetts, have invented an Improvement in Weight Hoisting and Releasing Mechanism, of which the following is a specification.

The invention described herein may be used by the Government, or any of its officers or employees in prosecution of work for the Government, or by any other person in the United States, without payment of any royalty thereon.

15 This invention relates, generally, to ingot breaking machines in which a weight elevating mechanism is employed, and in which the weight is automatically releasable at a predetermined point in the upward movement of the elevating mechanism; but the invention is applicable for use in other situations, as for instance, in pile or post drivers.

One of the objects is to provide novel means for automatically releasing the weight 25 at a predetermined point in the upward movement of the elevating mechanism.

Another object is to provide a novel mechanism for automatically engaging the elevating mechanism with the weight upon 30 descent of the weight elevating mechanism.

A subsidiary object is a novel construction, of the character noted, possessing extreme simplicity and also reliability and positiveness of action.

35 Other objects will appear as the specification proceeds and the nature of the invention is more fully disclosed.

With these objects in view, the invention resides, generally stated, in a weight elevating mechanism embodying complementary 40 grappling jaws, a locking member normally holding the jaws in closed or grappling position, and means for automatically moving said locking member to inoperative 45 position at a predetermined point in the upward movement of the elevating mechanism, thus permitting the jaws to open by the pressure of the weight, which thereupon drops.

50 More specifically, the invention resides in a novel construction of the jaws which are

provided with recessed portions, forming tongues which overlap both in the open and the closed position of the jaws, said tongues being provided with notches which register 55 when the jaws are closed.

The invention resides, finally, in certain specific improvements going to make up the ultimate perfection of the entire mechanism.

The invention in its preferred form is 60 disclosed in the accompanying drawings, in which:—

Figure 1 is a view in longitudinal section of the slide, the jaws and associated parts being shown in elevation; and 65

Fig. 2 is a detached detail view of the jaws.

Referring, now, in detail to the drawings:

The slide forming part of the weight elevating or hoisting mechanism may be of the usual construction, and, as here shown, comprises two parallel frame members or panels, one of which, designated by the numeral 1, is shown in the drawing, between which, near the ends thereof, are disposed, transversely, spacing members 2—2 secured to said frame members by suitable fastening means, such as bolts 3. Between the portions 4—4 of the frame members which 70 project beyond the spacing members 2—2 fit the guiding rails on which the slide moves, as usual, the drop weight, not shown, being grooved longitudinally at the sides thereof so as to fit the rails, the slide and 75 the weight thereby moving on the same rails.

Pivots supported on the pivot pins 5—5 extending transversely through the slide members 1—1 are grappling jaws 6—6, each 90 of which is provided with a cut-away portion 7 for the reception of the lateral portion or lip 8 of the other jaw. Opening movement of the jaws is limited by the lip or tongue 8 of each jaw contacting with the wall 9 of the cut-away portion 7 of the other jaw, as is obvious. By the construction described, it will be seen that the jaws overlap both in the open and closed position thereof. Each jaw is roughly of segmental 95 shape, so that, in the closed position thereof, they provide a circular aperture 100.

The overlapping portions 8—8 of the jaws are provided with notches 11—11, which, in the closed position of the jaws, register, as shown in Fig. 1. Each jaw may 5 be provided, adjacent said notch, with a transversely disposed flange 12, forming an extension of one of the side walls of the notch 11.

The invention comprehends suitable means 10 for normally locking the jaws in closed position. Obviously, such means may take a variety of forms. I have disclosed in the drawing my preferred form, which I will now describe.

15 Fulcrumed at 14 to the slide is a rock shaft 13 bent at 15 so as to project through a slot 16 in one of the frame members 1. After passing through said slot, said shaft is again bent to provide an arm 13' extending exteriorly of the slide parallel therewith. Carried by said rock shaft is a depending latch 20, which, when the jaws are closed, moves by gravity into the registering notches 11—11, thereby locking the jaws in such 20 closed position. The rock shaft carries a weight 17 at one end thereof, which weight may be adjustable on the rock shaft lengthwise thereof. Pivoted to the other end of the rock shaft, as at 19, is a dog 18 provided 25 with an inclined rear edge 19' bearing against a correspondingly shaped wall of the arm 13' thereby preventing movement of said dog independent of said arm in one direction. Arranged in the path of movement of the dog, as the slide is drawn upward, is a tripper 28 provided with a lower inclined or beveled surface 29, against which said dog contacts, thereby throwing the rock shaft and withdrawing the latch 20 from 30 the notches 11—11, whereupon the jaws open under the stress of the weight, and the weight drops. Upon descending movement of the slide, the arm of the dog 18 contacts with the upper end of the tripper 28 and 35 moves on its pivot so as to brush by the tripper. In the descending movement of the slide, the jaws remain open until the eye-bolt 22 passes between the open ends of the jaws and contacts with the bottom surface 40 of the overlapping portions 8—8, which upward stress on the jaws causes them to swing on their pivots to closing position. Conveniently, the eye-bolt 22, provided with a screw threaded portion 24, is screwed into 45 the weight, and this eye-bolt is engaged by the jaws 6—6 meeting through the eye 23.

60 Preferably, the links 25—25 are pivoted at their lower ends on the pivot pins 5—5, and a ring 26 passes through said links, the end link 27 of the hoisting chain engaging said ring 26.

Having thus fully described my invention, what I claim as new and desire to secure by Letters Patent is:

1. In a hoisting mechanism, the combination with a vertically movable slide, of grappling jaws carried thereby and provided with notches which register when the jaws are in closed position, a latch normally seated in said notches and preventing opening of said jaws, and means for automatically withdrawing said latch from said notches at a predetermined period in the upward movement of the slide. 65

2. In a hoisting mechanism, the combination with a vertically movable slide, of grappling jaws pivotally carried thereby and provided with notches which register when the jaws are in closed position, a latch normally seated in said notches and preventing opening of said jaws, and means for automatically withdrawing said latch from said notches at a predetermined period in the upward movement of the slide. 70

3. In a hoisting mechanism, the combination with a vertically-movable slide, of grappling jaws carried thereby and provided with recessed portions forming tongues, said tongues being provided with notches, which register when the jaws are in closed 80 position, a latch normally seated in said notches and preventing opening of said jaws, and means for automatically withdrawing said latch from said notches at a predetermined period in the upward movement of the slide. 85

4. In a hoisting mechanism, the combination with a slide, of grappling jaws carried thereby and provided with notches which register when the jaws are in closed position, a latch normally seated in said notches and preventing opening of said jaws, a rock shaft carried by said slide and carrying said latch, and means for rocking said shaft at a predetermined period in the upward movement of said slide, thereby withdrawing said latch from said notches. 100

5. In a hoisting mechanism, the combination with a slide, of grappling jaws carried thereby and provided with notches which register when the jaws are in closed position, a latch normally seated in said notches and preventing opening of said jaws, a rock shaft carried by said slide and carrying said latch, means for rocking said shaft at 110 a predetermined period in the upward movement of said slide, thereby withdrawing said latch from said notches, and a weight carried on the end of said rock shaft and slidable longitudinally thereon. 115

6. In a hoisting mechanism, the combination with a slide, of grappling jaws carried thereby and provided with notches which register when the jaws are in closed position, a latch normally seated in said notches and preventing opening of said jaws, a rock shaft carried by said slide and carrying said latch, said rock shaft being provided 125

at one end with a pivoted dog movable in one direction only on its pivot, and means for engaging said dog at a predetermined period in the upward movement of the slide. 5 7. In a hoisting mechanism, the combination with a slide carrying grapping jaws having notches which register when the jaws are in closed position and provided also with flanges extending along one side wall of said notches, of a latch normally seated in said notches, and means for withdrawing said latch at a predetermined point in the upward movement of the slide. 10
